UNITED STATES PATENT OFFICE.

GEORGE GILL AND EDWIN L. BRITTIN, OF DERBY, CONNECTICUT.

DESIGN FOR HANDLES FOR SPOONS, &c.

Specification forming part of Design No. **11,268**, dated June 24, 1879; application filed May 16, 1879.
[Term of patent 14 years.]

To all whom it may concern:

Be it known that we, GEORGE GILL and EDWIN L. BRITTIN, both of Derby, in the county of New Haven and State of Connecticut, have originated and designed a new Pattern for Handles of Spoons, Forks, and other articles of a similar nature, of which the following is a full, clear, and exact description, reference being had to the accompanying drawing, making part of this specification.

The drawing represents a face view of a handle containing our design.

The border of the handle is formed by a double thread or molding, *a*, and the edges diverge toward the top, and then curve toward each other and join the opposite ends of an arc, *b*.

The face of the handle contains two Eastlake ribbons, *c d*, which are in oblique positions, one near the top and the other at about the middle of the handle, and which are substantially parallel to each other. The portions of the border or double thread *a* at the sides of the handle terminate at the lower ribbon, *c*.

At one of the junctions of the upper ribbon, *d*, with the thread *a* is a corner ornament, *f*, while at one of the junctions of the lower ribbon, *c*, with such thread is a similar ornament, *g*, from which latter rises a stem, *h*, with flowers upon it.

About midway between the two ribbons *c d* on one side of the handle the thread *a* carries a button, *i*, from which rises a stem, *j*. This stem has the appearance of passing under the upper ribbon, *d*, and it has a flower at the upper end—namely, above the ribbon *d*—as at *k*, while upon the same rests a bird, *m*, with spread wings.

Within the arc-shaped portion *b* of the border is situated a flower, *l*, the stem of which has the appearance of extending under the upper ribbon, *d*.

What we claim as new, and desire to secure by Letters Patent, is—

1. The design for the handles of spoons and like articles, consisting of a double thread upon the edge of the handle, a stem rising from a button on this thread, with a flower at its upper end and a bird resting upon such stem, as shown and described.

2. The design for the handles of spoons and like articles, consisting of two oblique Eastlake ribbons substantially parallel to each other, a double thread upon the edge of the handle terminating at the lower ribbon, and a stem rising from a button on said thread, with a flower at its upper end, as shown and described.

3. The design for the handles of spoons and like articles, consisting of the double thread following diverging edges and curved inwardly, near the tip of the handle, to join the top curve or arc, two oblique Eastlake ribbons substantially parallel to each other, a stem rising from a button on the double thread and having a flower at its top, and a flower situated within the top curve or arc, substantially as described.

In testimony that we claim the foregoing we have hereunto set our hands and seals this 5th day of May, 1879.

GEORGE GILL. [L. S.]
E. L. BRITTIN. [L. S.]
